UNITED STATES PATENT OFFICE.

GUY MAGEE, JR., OF WILMETTE, ILLINOIS.

PACKAGE.

1,036,661.

Specification of Letters Patent. Patented Aug. 27, 1912.

Application filed October 23, 1911. Serial No. 656,123.

To all whom it may concern:

Be it known that I, GUY MAGEE, Jr., citizen of the United States, residing at Wilmette, in the county of Cook and State of Illinois, have invented a certain new and useful Improvement in Packages, of which the following is a full, clear, concise, and exact description, reference being had to the accompanying drawings, forming a part 10 of this specification.

My invention relates to packages and finds an important embodiment in devices for packing collars or cuffs.

The invention has for its main object the 15 provision of a container whose size is variable to suit the quantity of the contents. To this end I preferably employ a containing sheet for inclosing the contents and which may have its edge portions sufficiently 20 gathered together to limit the space inclosed by the sheet to that which would be properly occupied by the contents.

In the preferred embodiment of the invention I employ a contractible and expen- 25 sible package contents inclosing band that may be adjusted snugly to fit the contents it incloses whereby a definite shape may be imparted to the package and the containing sheet may be relieved of strain that would 30 otherwise be imposed thereupon. I do not wish to be limited however, in all embodiments of the invention, to the employment of the aforesaid band. As my invention is 35 preferably practised I also employ a fastening device for holding the gathered portions of the sheet, this fastening device desirably including two members in its formation, one surrounding and the other surrounded by the gathered portions of the sheet which 40 are held between the fastening members so that the sheet is caused snugly to fit the package contents and the band inclosing the same, if such band be employed. For the sake of convenience I desirably equip one 45 of the fastening members with a receptacle that may be used for containing collar buttons or other small devices.

I will explain my invention more fully by reference to the accompanying drawing 50 showing the preferred embodiment thereof in the form of a holder for collars and in which drawing—

Figure 1 is a sectional view; Fig. 2 is a plan view on a much reduced scale, the ex- 55 pansible and contractible band being omitted and the sheet being laid flat; Fig. 3 is a

sectional view on line 3 3 of Fig. 1; Fig. 4 is a perspective view of the inner fastening member; and Fig. 5 is a perspective view of the contractible and expandible band. 60

Like parts are indicated by similar characters of reference throughout the different figures.

An expandible and contractible contents inclosing band *a*, made preferably of spring 65 metal, has its ends in overlapping relation, these ends passing through a loop *b* which carries a thumb screw *c* in one of its long sides, the inner end of the thumb screw being adapted to project within the space of 70 the loop and there clampingly to engage a portion *c'* with the overlapping ends of the band to hold them in fixed relation with each other. When the thumb screw is loose the peripheral length of the band may be 75 adjusted to suit the space that should be occupied by the package contents, whereafter the adjustment may be maintained by the screw as has been described.

In order to prevent the collars at the 80 center of the package from being wound too tight and in order to provide an object about which the collars may be disposed, I employ a mandrel *d* that is substantially 85 centrally disposed with respect to the band *a*, the collars being placed between the mandrel and the band, the band thus surrounding the collars while the mandrel is surrounded by the collars. One end of this mandrel is desirably provided with a partition *e* that serves to constitute a wall of 90 a receptacle for buttons, etc., this receptacle being provided with a cover *f* that fits the mandrel. A sheet *g* of some flexible material such as cloth is permanently secured to the mandrel but is desirably unattached to the band but which preferably overlies the same to engage it. After the collars, or other contents, have been disposed about the mandrel and the peripheral length of 95 the band has been adjusted to suit the space to be occupied by the collars, the sheet is gathered over the band and the package contents and the gathered edges of the sheet are tucked into the mandrel whereafter a fastening member is inserted within the mandrel to hold the gathered edges of the sheet against the mandrel, the mandrel thus becoming a fastening member that is complementary to the fastening member that is 100 inserted within the mandrel. The inner fastening member is preferably externally 105 110

faced with plush and is desirably in the form of a strong band spring that requires contraction in order to be received within the mandrel, and which, by its expansion, holds the gathered edge portions of the sheet against the mandrel. In order to facilitate the insertion and removal of the spring fastening member *h*, I provide the same with inturned thumb and finger holds.

10 By the construction which has been described the package or container is flexible in size to suit the package contents. Moreover the arrangement is such that there need be no crack or crevice for the admission of 15 foreign matter to the package interior.

The fastening device which I preferably employ includes two members, the member *h* being surrounded by the gathered edges of the sheet while the supplemental member *d* surrounds the gathered edges of the sheet. There is thus provided a fastening device having two members for holding the gathered portion of the sheet therebetween, the inner fastening member *h* operating to 25 hold the gathered edges of the sheet by pressing outwardly upon such sheet edges while the hollow outer fastening member *d* receives the tucked in edges of the sheet in position to permit the inner fastening member to press the gathered edges of the sheet against the outer fastening member and thereby hold such edges.

In the event of the omission of the mandrel *d* the spring fastening member could 35 be employed to hold the collars by pressing the cloth sheet directly against the collars, and in some forms of the invention the entire fastening mechanism at the central portion of the structure could be omitted, in 40 which case the edge portions of the cloth could be tucked into the central space or otherwise held.

While I have herein shown and particularly described the preferred embodiment 45 of my invention, I do not wish to be limited to the precise construction illustrated as changes may readily be made without departing from the spirit of the invention.

Having thus described my invention I 50 claim as new and desire to secure by Letters Patent the following:—

1. A package including a contractible and expansible package contents inclosing band; a containing sheet for engaging said band 55 and inclosing the package contents and having edge portions adapted to be gathered in close proximity; and a fastening device

having two members for holding the gathered portions of the sheet therebetween.

2. A package including a contractible and 60 expansible package contents inclosing band; a containing sheet for engaging said band and inclosing the package contents and having edge portions adapted to be gathered in close proximity; and a sheet fastening 65 member for holding the gathered portions of the sheet.

3. A package including a containing sheet for inclosing the package contents having its outer border portions adapted to be 70 gathered in close proximity; and a fastening device having a sheet holding member surrounding and another sheet holding member surrounded by the gathered outer border portions of the sheet.

75 4. A package including a containing sheet for inclosing the package contents having its outer border portions adapted to be gathered in close proximity; and a fastening device having two members for holding 80 the gathered outer border portions of the sheet therebetween.

5. A package including a containing sheet for the package contents having its outer border portions adapted to be gathered in 85 close proximity; and a sheet fastening member surrounded by and adapted to hold the gathered outer border portions of the sheet, said fastening member operating to hold the gathered edges of the sheet by pressing 90 outwardly upon such sheet edges.

6. A package including a contractible and expansible contents inclosing band; a central member between which and the band the package contents are to be disposed; and a containing sheet engaging said band and further inclosing its contents, said central member being of a formation to permit the gathered edges of the sheet to be held in engagement therewith.

95 7. A package including a central member; and a containing sheet between which and the central member the package contents may be disposed, said central member being of a formation to permit the gathered 105 edges of the sheet to be held in engagement therewith.

In witness whereof, I hereunto subscribe my name this seventeenth day of October A. D., 1911.
